UNITED STATES PATENT OFFICE.

WILLIAM J. TANGERMAN, OF HAMMOND, INDIANA.

PLATE-FABRICATING MACHINE.

Application filed January 27, 1922. Serial No. 532,240.

To all whom it may concern:

Be it known that I, WILLIAM J. TANGERMAN, a citizen of the United States, and a resident of Hammond, county of Lake, and

5 State of Indiana, have invented a certain new, useful, and Improved Plate-Fabricating Machine, of which the following is a specification.

10 My invention relates generally to improvements in plate fabricating machines, but relates more particularly to machines for perforating or punching plates.

15 In the manufacture of tanks, boilers, chimneys, and many other articles that are fabricated by the use of metal plates, it is necessary to provide the plate or plates with a large number of holes. The number of these holes, the placing thereof, the size and disposition vary through a great range. In 20 order to punch a plate having variously spaced holes it has heretofore been necessary to set up the punch press with as many punches as there are holes disposed across the sheet, and as there frequently are a large 25 number this is an extremely slow and laborious operation. In many instances one hole will be offset from a hole which is needed at some other point along the sheet, such a short distance that it is impossible to 30 provide punches sufficiently close to make the necessary perforations. This necessitates the punching of so many holes as can be made by the punches that can be accommodated in the machine and then the sep- 35 arate punching of the other holes by shifting the plate manually between the punch and die. This latter operation is an extremely slow and tedious one due to the fact that the center of the opening must be 40 spotted under the punch and considerable time is lost in thus locating the sheet or plate. Also, under the practice heretofore prevailing, it has been an expensive operation to punch a relatively few plates and 45 this has added greatly to the cost of fabricated articles made from plates.

The general object of my invention is to provide a machine wherewith plates can be punched or perforated at less expense.

50 Another object of my invention is to provide a machine wherewith plates can be punched quickly and easily, and wherewith all of the desired holes in the plates can be made in one passage of the plate or sheet through the machine.

55 Another object of my invention is to pro-

vide a machine wherewith the heretofore manual shifting of the plate for the purposes of spotting hole centers may be eliminated, and simple, quick, and easily operable 60 means provided to accomplish the desired result.

I aim also to provide a machine of the character mentioned which can be set up to punch a given number and arrangement of 65 holes quickly, easily and at little expense.

Other objects of my invention are to provide a machine which, relative to the work to be performed, shall be simple and which shall be well adapted to operate accurately 70 over a long period of time.

My invention consists generally in a machine of the form, arrangement, construction and co-operation of the parts whereby the above named objects, together with 75 others that will appear hereinafter, are attainable; and my invention will be more readily understood, by reference to the accompanying drawings, which illustrate what I consider, at the present time, to be the 80 preferred embodiment thereof.

In said drawings:

Fig. 1 is a right hand side elevation of a machine embodying my invention, certain of the parts being shown in section better 85 to illustrate the construction thereof.

Fig. 2 is a front elevation of the machine, portions thereof being broken away to disclose parts which otherwise would be hidden from view.

Fig. 3 is a fragmentary plan view of the machine, certain of the superstructure being removed, better to disclose the pertinent parts of the machine.

Fig. 4 is a detail sectional view substantially along the line 4—4 of Fig. 2, but upon an enlarged scale.

Fig. 5 is a detail view along the line 5—5 of Fig. 4.

Fig. 6 is an enlarged section on the line 100 6—6 of Fig. 1; and

Fig. 7 is a view along the line 7—7 of Fig. 6, certain of the parts being broken away to disclose the interior construction.

The machine shown in the drawings comprises a centrally arranged heavy casting frame 1 which is suitably secured upon the floor or support, 2. The frame 1 is provided with an upstanding portion 3, in which there is suitably mounted, for rotation, a large shaft 4. The shaft 4 may be suitably driven from the pulley 5 which is

operatively connected by means of suitable clutch mechanism 6. 7 and 8 are vertically arranged guides in which a sliding head 9 is guided to and from its working position. 5 For moving the head 9 back and forth, arms 10 and 11 are provided which, in turn, engage eccentrics mounted upon the shaft 4. Mounted on the underside of the movable head 9, at opposite ends thereof, will be 10 found a plurality of punches 12 and 13, respectively, which are suitably aligned with the die blocks 14 and 15, respectively that are mounted upon the stationary bed portion 16 of the machine. While each group 15 of dies 12 and 13 are here shown as six in number, this number may be more or less, depending upon the work to be performed. As will appear shortly, the dies 12 and 13 are utilized to punch the side edges of the 20 sheet. Instead of spacing dies across the movable head 9 for punching the holes in the end edges of the sheet, as well as other holes that may be desired between the side edges, I have provided a novel construction 25 for punching such holes. For this purpose, I provide a horizontally movable punch head 17 in which are mounted a plurality of punches 18. The movable punch head 17 is provided with a dove-tail portion 19 which 30 enters the guide way 20 that extends from side to side of the machine and which is carried by the vertically movable head 9. Directly beneath the punches 18 is a die 35 block 21 which likewise is mounted for horizontal sliding movement, being positioned in the horizontal guideway 22 that is formed in the bed of the machine. Interposed between the punches 18 and the die block 21 is a stripper plate 27 which is moved back and forth, at the same time that the punch holder 40 17 and the die block 21 are moved, so that it always maintains its proper position between the said parts.

The punch holder 17 and the die block 21 receive their movement through the instrumentality of pusher arms 28 and 29, respectively, which are connected to a carriage 30. The pusher arm 28 is pivotally connected to the punch holder 17, as indicated 45 at 31, and to the carriage, as indicated at 32. Pivots 33 and 34 connect the lower push rod 29 to the die block 21 and the carriage 30, respectively. These pivots permit the necessary freedom of movement. 50

The stripper plate 27 receives its movement by means of the link 35 that is connected to the upper pusher arm 28. While the stripper plate 27 must move back and forth with the punch holder 17 and the die 55 block, 21, in order to function properly, it must prevent the upward movement of the plate that has been punched, and to prevent such undesired movement it is provided with end portions 36 and 37, respectively, that 60 are in slidable engagement with the lower

part of I-beams 38 and 39, respectively. These I-beams extend across the machine and are suitably secured to the stationary parts of the frame of the machine, as indicated at 40 and 41, respectively. 70

The plate to be punched is indicated by means of dotted lines in Fig. 1 of the drawings and bears the reference character 42 from which it will be evident that it passes under the stripper element 27 and over the die block 21. Means are provided for moving the plate through the machine so that the punches 12 and 13 may operate upon the desired edge portions thereof and by means of the carriage 30 and the mechanism carried thereby, the movable punches may be quickly and easily moved to the desired position. 75

I shall first describe the means for moving the plate, through the machine, and shall then follow with a description of the mechanism for moving the carriage 30 and for stopping it at desired points. 80

For moving the plate through the machine I have provided a carriage which, as here shown, is composed of I-beams 43 and 44 arranged in parallel relation. These I-beams extend entirely through the main frame of the machine as well as a considerable distance forwardly and rearwardly 85 thereof. These I-beams are cross-connected at their front and rear ends by means of the U-shaped span members 45 and 46. The members 45 and 46 are detachably secured to the I-beams 43 and 44 as by means of 90 clips 47 and 48, but when the elements 45 and 46 are secured to the I-beams, the I-beams are rigidly connected so as to constitute a carriage of such construction that movement of any of the parts thereof causes 95 like movement of all of the parts. For the purpose of moving the carriage, the I-beams 43 and 44 are provided with gear racks 49 and 50, respectively, upon their bases, which, 100 in turn, mesh with pinions 51 and 52 that are carried upon a cross shaft 53. The cross shaft 53 is mounted for rotation in suitable bearings supported from stationary parts of the machine frame, and at its outer end is provided with a hand wheel 54. Thus, by 105 moving the hand wheel 54 in one direction, the carriage may be moved through the machine from front to rear, and by reversing the hand wheel, the carriage may be restored to its initial position. The I-beams 110 of the carriage, it will be observed, are mounted upon a plurality of rollers 55 that are carried in suitable bearings 56, which 115 in turn are mounted upon stationary parts of the machine frame. As is best shown in 120 Figs. 2, 3 and 6, the rollers 55 are arranged in pairs, spaced apart to accommodate the gear racks 49 and 50, which depend from the 125 under parts of the I-beams 43 and 44.

For supporting the plate to be perforated 120

or punched, a plurality of rollers 57 are provided which, likewise, are suitably journaled in bearings carried by stationary parts of the machine frame. The rollers 57 not only 5 sustain the plate or sheet to be punched, but also enable a very easy movement thereof through the machine so that little effort is required on the part of the operator.

The bridge 45 is provided with clamps 58 and 59 that carry set screws at their ends whereby the plate 42 may be rigidly gripped so that movement of the bridge 45, as occasioned by movement of the carriage to which it is attached, will move the plate 10 through the machine. Likewise the bridge or member 46 is provided with spaced clamps 60 and 61 whereby, at the proper time, the plate may be gripped so that it will be held rigidly at both ends, so that the 15 whole moves as a unit along the bed of the machine. When the plate is first started into the machine, however, it receives all of its movement from the bridge pusher 45. As soon, however, as the first few holes are 20 punched along the side of the plate, the bridge structure 46 is moved toward the plate until the clamps engage the same, at which time, the clamps are tightened and the bridge 46 secured to the I-beams of the carriage. As the rear end or edge of the plate 25 is approached and before the plate can be entirely moved through the machine, the clamps carried by the bridge 45 are released and the final movement through the machine 30 is occasioned by the pull of the bridge 46.

For punching holes along the side edges of the sheet, it is obviously necessary to stop the plate at certain points where it rests until the punches perforate the sheet and 35 are stripped therefrom and then to move the plate to the next position. In order that this may be quickly and accurately accomplished without the need of any particular skill upon the part of the operator, I have 40 provided means whereby the carriage can be stopped at any of a very large number of pre-determined points, and since the plate moves with and by movement of the carriage, this will automatically position the 45 plate as required. To this end, I have provided a plurality of carriage spacing elements 62, 63, 64, and 65 which are designed for co-operation with mechanism carried by the bridge 45 and a plurality of elements 66, 50 67, 68 and 69 for co-action with mechanism carried by the bridge 46. The general construction and mounting of the various members 62 to 69, inclusive, is alike, and hence a description of one will serve for all. To 55 this end, considering the element 65, it will be found to be a relatively thin elongated bar or blade having upon its upper surface, a plurality of teeth or indentations 65'. The bridge 45 carries a plurality of pawls or 60 levers 70, 71, 72 and 73 for co-action respec-

tively with the elements 62 to 65 inclusive. Only one of the pawls or levers 70 to 73 inclusive, will be used at a time, and I therefore, provide means whereby all except one thereof may be held upwardly or in inoperative position. This means comprises a cross-shaft 74 upon which a plurality of differently formed cam surfaces are provided, these cam surfaces being so disposed that by rotating the shaft 74, the desired 75 lever or pawl 70 to 73 will be lowered into operative position whilst the remaining levers are held in inoperative position.

The bridge 46 is likewise provided with a plurality of pawls or levers of a similar construction for co-action with the respective spacing members, 67 to 69 inclusive. It should be obvious that as the carriage is moved, the operative pawl will drop into any depression that may be made in the spacing bar 85 with which it co-acts and the operator knows that the plate is then positioned for punching and may operate the punch without the necessity of even examining the plate to determine its position under the punches. By 90 thus providing a plurality of differently formed spacing bars, the machine is adapted to punch plates having holes spaced in great variety. If a relatively few plates having 95 hole spacings such as cannot be provided with the usual spacing bars, it is a very simple matter to make a spacing bar, remove one of the spacing bars from the machine, and insert the one thus produced. It thus 100 becomes clear that the side edges of the plates which are perforated by the punches 12 and 13 may be quickly, easily and accurately fabricated.

I have also provided means whereby holes 105 may be punched along the ends of the sheet, as well as elsewhere, intermediate the ends and inwardly of the holes that can be perforated by the groups of punches 12 and 13. All of such holes are formed by the punches 110 18 that are carried in the movable head 17, before described. In order to quickly and easily position the punches 18 and the die block 21 with which they co-act the carriage 30 is provided with a plurality of pawls or 115 levers 75, 76, 77 and 78 for engagement with a plurality of spacing bars 79, 80, 81 and 82. A cross shaft 83 is provided on which there 120 are mounted cam surfaces so formed and positioned so that any one of the pawls 75 to 77, inclusive, may be moved to operative position, whilst the remaining pawls are held upwardly in inoperative position. That is to say, assuming that four spacing bars are provided and four pawls for co-action therewith, as here disclosed, three of the pawls 125 will always be held in inoperative position. Thus, the pawl which is in operative position will drop into any depression that is formed in such of the spacing bars 79 to 82 inclusive with which it co-acts. These depressions 130

in the spacing bars are somewhat diagrammatically illustrated in the drawings and bear the reference character 84.

In starting the plate through the machine, 5 the end first started is usually to be punched and, if this is the case, the plate is pushed forward to the proper position by the bridge 45, before described, carriage 30, having previously been moved to the right from the full line position shown in Fig. 2, so that the 10 punches 18 and the die block 21 will be positioned adjacent what would be the right hand edge of the sheet or the near edge as viewed in the plan view of Fig. 3. The carriage 30 is then positioned by moving it until the operative pawl drops into the desired depression, at which time, the clutch 6 is moved to operative position causing, as before described, movement of the head 9, 15 downwardly, which results in carrying the punches 17 with it and through the plate to be perforated. The plate, as before described, is stripped from the punches by means of the stripper elements 37. The carriage 30 is then moved to the left until the operative pawl comes into engagement with the next or desired depression, where it is stopped and the machine again operated to perforate the plate at that point. Since a 20 relatively large number of punches may be mounted in the movable head 17, the necessary holes along the end of the plate can be very quickly, easily and accurately formed. With respect to all of the punches 25 that are carried by the movable head 17, as well as the punches designated as 12 and 13, it will be understood that each punch is provided with means for causing it to become inoperative so that any or all, or so many, 30 of any of the groups of punches as may be desired will be operative to perforate the plate.

For moving the carriage 30 back and forth, it is mounted upon rollers 85 that ride upon rails 86, and the pusher arm 39 that is secured to the carriage 30 is provided with a gear rack 87. A hand wheel 88 is provided for rotating the shaft 89 on which is mounted a pinion 90 engaging with an idler gear 91 that meshes with a pinion 92 which, in turn, is in engagement with the gear rack 87. It is obvious that by means of the hand wheel, the carriage 30 may be moved back and forth, as desired.

55 Having perforated the plate entirely across the end, the whole plate is moved through the machine, as before described, mean time being provided with the necessary holes along its side edges by the operation of the punches 12 and 13.

For perforating holes intermediate the side edges, as well as intermediate the end edges of the sheet, the movable punches 17, 60 likewise serve admirably in conjunction with the carriage that moves the plate through

the machine, for it will be understood that the plate can be stopped and positioned at the desired point through the instrumentality of the gage bars, before described, and then to position the punches 18, it is but 70 necessary to move the carriage 30 until the operative pawl reaches the desired depression, and the machine is ready to perform the punching operation. Such spaced holes have usually been made heretofore by shifting the plate around until the center of the opening was spotted under the punch. This was a slow, and laborious operation, and one which required considerable skill if any degree of accuracy and speed was to be attained. In order to avoid this difficulty it has heretofore been the practice to set up a punch for every transversely positioned disaligned hole, but this is only practicable 75 when a very large number of sheets are to be perforated, as the time required for such set up is quite long. Such practice, furthermore, is not satisfactory because if some of the holes are disaligned, but a fraction of an inch, they cannot be punched in the same operation for the reason that the punches cannot be banked in the machine sufficiently close to accomplish that result. On the other hand, with my machine, all of the 80 holes can be punched, no matter where they may be positioned, nor how slightly disaligned one with respect to the other, and, furthermore, even a relatively few plates can be punched because it is only necessary to provide the relatively inexpensive and easily 85 produced spacing bars, before described.

90 Inasmuch as this disclosure will readily suggest to others, modified constructions, whereby the substantial objects, and purposes of my invention may be attained, I 95 do not wish to be limited to the specific construction herein shown and described, except only as may be necessary by limitations in the hereunto appended claims.

I claim:

1. A machine of the class described, embodying therein a movable punch holder, a movable die block, a stripper element interposed between but supported independently of said punch holder and die block, and means for synchronously moving said stripper element, movable punch holder and co-operative die block.

115 2. A machine of the class described, embodying therein a movable punch holder, a movable die block, a stripper element interposed between but supported independently of said punch holder and die block, and means for locating said movable punch holder, stripper element, and die block at any desired position along a given line.

120 3. A machine of the class described, embodying therein a movable punch holder, a movable die block, a stripper element interposed between but supported independently of

ently of said punch holder and die block, and means for moving said movable punch holder, stripper element and die block to any desired position.

5 4. A machine of the class described, embodying therein a movable punch holder, a movable die block, a stripper element interposed between but supported independently of said punch holder and die block, and means for locating said movable punch holder, stripper element, and die block at any desired position along a given line, said means including a spacer bar.

10 5. A machine of the class described, embodying the carriage, punch holder, die block and stripper element, together with means for operating said carriage.

11. A machine of the class described, embodying therein a movable punch holder, a movable die block, a stripper element interposed between but supported independently of said punch holder and die block, and means for locating said movable punch

5. A machine of the class described, embodying therein a movable punch holder, a movable die block, a stripper element interposed between but supported independently of said punch holder and die block, and means for locating said movable punch holder, stripper element, and die block at any desired predetermined position along a given line, said means including a spacer bar.

15

holder, stripper element, and die block at any desired position along a given line, said means including a spacer bar, a carriage having means engageable with the spacer bar, means connecting the punch holder, die block and carriage, together with means for operating the carriage.

20

12. A machine of the class described, embodying therein a movable punch holder, a movable die block, a stripper element inter-

85

6. A machine of the class described, embodying therein a movable punch holder, a movable die block, a stripper element interposed between but supported independently of said punch holder and die block, and means for locating said movable punch holder, stripper element and die block at any desired position along a given line, said means including a removable spacer bar.

means including a removable spacer bar.

7. A machine of the class described, embodying therein a movable punch holder, a movable die block, a stripper element interposed between but supported independently of said punch holder and die block, and means for moving said movable punch holder, stripper element, and die block to any desired position along a given line, said means including a removable spacer bar.

13. A machine of the class described, embodying therein a movable punch holder, a movable die block, a stripper element interposed between but supported independently of said punch holder and die block, and means for locating said movable punch holder, stripper element and die block at any desired position along a given line, said means for operating the carriage.

100

105

8. A machine of the class described, embodying therein a movable punch holder, a movable die block, a stripper element interposed between but supported independently of said punch holder and die block, and means including a plurality of spacer bars, a carriage having means engageable with the spacer bars, means connecting the punch holder, die block, and carriage, together with means for operating the carriage. 110

means for locating said movable punch holder, stripper element and die block at any desired predetermined position along a given line, said means including a removable spacer bar.

14. A machine of the class described, embodying therein a movable punch holder, a movable die block, a stripper element interposed between but supported independently of said punch holder and die block, and means for locating said movable punch

9. A machine of the class described, embodying therein a movable punch holder, a movable die block, a stripper element interposed between but supported independently of said punch holder and die block, and means for moving said movable punch holder, stripper element, and die block to any desired position along a given line, said means including a removable spacer bar. 120
55 10. A machine of the class described, embodying therein a movable punch holder, stripper element, and die block at any desired position along a given line, said means including a plurality of removable spacer bars, a carriage having means engageable with the spacer bars, means connecting the punch holder, die block and carriage, together with means for operating the carriage. 125
60 11. A machine of the class described, embodying therein a movable punch holder, stripper element, and die block at any desired position along a given line, said means including a plurality of removable spacer bars, a carriage having means engageable with the spacer bars, means connecting the punch holder, die block and carriage, together with means for operating the carriage. 125

10. A machine of the class described, embodying therein a movable punch holder, a movable die block, a stripper element interposed between but supported independently of said punch holder and die block, and

15. A machine of the class described embodying therein, a horizontally movable punch holder, a die block movable therewith, a stripper element interposed between but supported independently of said punch hold-

- er and die block, means for locating said horizontally movable punch holder, stripper element and die block at any desired position along a given line, and means for moving a plate at any angle to the line of horizontal movement of said punch holder.
16. A machine of the class described embodying therein, a horizontally movable punch holder, a die block movable therewith, a stripper element interposed between but supported independently of said punch holder and die block, means for locating said horizontally movable punch holder, stripper element and die block at any desired position along a given line, and means for moving a plate at an angle to the line of horizontal movement of said punch holder and locating the plate at any desired position.
17. A machine of the class described embodying therein, a horizontally movable punch holder, a die block movable therewith, a stripper element interposed between but supported independently of said punch holder and die block, means for locating said horizontally movable punch holder, stripper element and die block at any desired position along a given line, said means including a carriage, means connecting the carriage punch holder, die block and stripper element, together with means for operating said carriage, and means for moving a plate at an angle to the line of horizontal movement of the said punch holder.
18. A machine of the class described embodying therein, a horizontally movable punch holder, a die block movable therewith, a stripper element interposed between but supported independently of said punch holder and die block, means for locating said horizontally movable punch holder, stripper element and die block at any desired position along a given line, said means including a carriage, means connecting the carriage punch holder, die block and stripper element, together with means for operating said carriage, and means for moving a plate at an angle to the line of horizontal movement of said punch holder and locating the plate at any desired position.
19. A machine of the kind described embodying therein a bed plate member, a head member mounted for vertical movement toward and away from the bed plate, a die block movable on the bed plate member, a punch holder movable on the head member, a stripper element interposed between the die block and punch holder, means for slidably supporting the stripper element upon one of said members, and means for synchronously moving said die block, punch holder and stripper element.
20. A machine of the kind described embodying therein, a bed plate, a movable die block thereon, a head mounted for vertical movement toward and away from said die block, a punch holder movable on said head, a stripper element interposed between said die block and punch holder, means on said head to the front and rear of said punch holder upon which the stripper element is movably mounted, and means for synchronously moving said die block, punch holder and stripper element.
21. A machine of the kind described embodying therein, a bed plate, a movable die block thereon, a head mounted for vertical movement toward and away from said die block, a punch holder movable on said head, a stripper element interposed between said die block and punch holder, rails on said head to the front and rear of said movable punch holder and extending parallel with the direction of movement thereof, means for movably supporting said stripper element on said rails, and means for synchronously moving said die block, punch holder and stripper element.
22. A machine of the kind described embodying therein, a bed plate, a movable die block thereon, a head mounted for vertical movement toward and away from said die block, a punch holder movable on said head, a stripper element interposed between said die block and punch holder, means on said head to the front and rear of said punch holder upon which the stripper element is movably mounted, means for imparting movement to said die block and punch holder, and means pivotally connected to said last mentioned means and said stripper element so that said stripper element moves synchronously with said punch holder and die block.

In testimony whereof, I have hereunto set my hand, this 20th day of January, 1922.

WILLIAM J. TANGERMAN.
